TAPPING AND REFILL-CONTROLLING
DEVICE

Christoph Karageorgieff, Vienna, Austria

Application November 9, 1935, Serial No. 49,107
In Austria March 29, 1934

6 Claims. (Cl. 217—108)

I have filed applications in Austria on the 29th March 1934 and in Austria on the 5th December 1934 and of which the following is a specification.

This invention relates to tapping and refilling devices equipped with controllable locking means, for use on containers for marketable liquids, and more particularly on barrels, drums and the like. The known types of commercial barrels for marketable liquids such as for example gasoline, lubricating oil, edible oil, kerosene, or the like are as a rule provided with two openings which are adapted to be closed by means of screw plugs and sealed as a precaution against being tampered with during transport and storage. All the known types of fluid containers of this description have the disadvantage that there is no check on refilling. The containers in question are generally filled by the producers or suppliers of the contents with a liquid of a certain definite and standard quality, for example lubricating oil or gasoline; now it is in the interests of the supplier to prevent dealers and others from filling such barrels or other containers, when empty, with poorer quality products, and deceiving the public by selling these as products of the recognized superior quality denoted by the marking or appearance of the containers. A further disadvantage resides in the fact that the barrels or other containers are loaned to the dealers free of charge by the producers of the marketable contents, and are generally retained by the dealers for an unconscionably long time, and are often damaged or exchanged before being returned.

The present invention has for its object to obviate all these drawbacks, and above all to prevent the possibility of barrels being refilled, after the sale of the original contents, with other products by unauthorized persons (more particularly dealers).

With these and other objects in view, the present invention provides a tapping and refilling device equipped with locking means, for use in connection with containers (more particularly barrels and the like), comprising in combination a tapping cock consisting of a casing and a fitted plug, ports in the said casing and plug adapted to be brought into and out of register by rotation of the said plug, disengageable retaining means associated with the said plug and casing for normally retaining the said plug against withdrawal from the said casing, an outwardly opening valve interposed in the outflow path of the said cock, and a lock built into the said cock in operative association with the said retaining

means, for the purpose of enabling the said plug to be withdrawn from the said casing, thereby providing a refill aperture, after disengagement of the said retaining means in dependence on the operation of the said lock.

5

Containers (casks) have indeed already become known having filling and tapping devices governed by locking mechanism. With these known devices, however, the lock must be unlocked and the cock placed in the open position both for drawing off liquid from the cask and also for refilling the cask with fresh liquid. The purpose of the present invention cannot be fulfilled by a device of this nature, since the dealer would also be required to have a key, in order to be in a position to undo the lock to open the cock for tapping purposes, in which case he is also in a position to refill the container when empty, which is precisely what is to be avoided by the present invention.

10

Fig. 1 shows a modified form of construction with fixation of the plug of the cock against the casing of the cock.

15

Fig. 2 is a section taken on the line 2—2 of Fig. 1.

20

Figs. 3—6 show a modified form of construction of the invention, Fig. 3 being a vertical longitudinal section, Fig. 4 a front elevation, Fig. 5 a section taken on the line 5—5 of Fig. 3, and Fig. 6 a rear elevation.

25

Fig. 7 shows a further modification in side elevation.

30

Fig. 8 is a section on the line 8—8 of Fig. 7.

35

In the present form of construction shown in Figs. 1 and 2 the arrangement and assembly of the parts 1 to 29 is the same as in the preceding form of construction, described and illustrated in the patent application Ser. No. 12,278, filed March 21, 1935, of which the present application is a continuation in part, only with the difference that the plug 5 of the cock is arranged to be susceptible of withdrawal from the casing 4 while being otherwise locked in the casing inaccessible to unauthorized persons. For this purpose the rear end of the plug 5 of the cock is provided with a groove 30 and a collar 31, while to the pin 23 of the cylinder lock there is keyed or otherwise secured a hook-shaped latch 32 which is adapted to be pivotally swung, on the operation of the lock, so that its concave edge 50 fits into the groove 30. Both the inner side of the collar 31 and also the corresponding end surface of the latch 32 can be made slightly inclined, for the purpose of holding the plug firmly fitted into the casing by the said latch.

55

If the hook-shaped latch be swung in an anti-clockwise direction (as seen from behind), the plug of the cock can at once be withdrawn from its casing for the purpose of enabling the container to be refilled.

The constructional example now to be described, which is shown in Figs. 3 to 6, provides the possibility of removing the non-return valves, the parts of the locking means, and the latch together with the plug of the cock. The plug 5 of the cock can at the same time be made suitably large or can be of larger diameter than that of the previously discussed forms of construction, with the incidental result that the large aperture 15 in the casing conditioned thereby permits of more rapid filling of the container. Into the cock plug itself, and disposed in an axial direction, there is built a cylinder lock 6. The central portion 23 of this lock is provided with a pin 23^a to which there is attached at the rear end a cam slot disc 33. In the suitably eccentrically disposed slots 33^a of this disc there engage permanently the studs 34 on the one end of each of two latches 35 the other ends of which are furnished with pivot 25 pins 36 which are pivotally mounted in suitable recesses in the rear end surfaces of the casing 4. By rotation of a thrust key 21, which is inserted in the slot 23^b in the part 23, and with it of the pin 23^a in a clockwise direction the latches 35 30 become swung outwards, so that they are brought into the locking position shown in Fig. 6. A stuffing box 13 prevents the escape of liquid through the lock mechanism.

The cock plug 5 is provided with two diametrically opposed recesses 38 and 39 of which, in the position shown in Fig. 3, the recess 38 admits air into the vent pipe 14 and thence into the container, while the recess 39 permits liquid to flow out of the barrel through the port 11 and over the pouring lip 4^a. The port 11 is controlled by a non-return valve consisting of a cambered flap 41 of a curvature corresponding to that of the casing 4 and articulated to the cock plug by means of a stirrup 42. The cock plug 5 is provided at the front end with a particularly large head 43 which carries the handle 9 and protects the pouring lip 4^a. In order to render the flap 41 less accessible, the casing 4 is provided at the front with an upstanding flange 44 which surrounds the head 43 of the cock plug with slight clearance, while on the under side of the cock plug there is provided a rib 46. The part 44 is also provided for the purpose of preventing fouling of the outflow passages. A sheet metal ring 49 cast in the casing permits of the subsequent application of the device to already existing and used containers, for which purpose the said ring is united to the end of the container for instance by welding. For the purpose of refilling the container the cock plug 5 is taken out of the casing 4 after the operation of the lock 6 which brings the latches 35 out of the locking position.

Figs. 7 and 8 show a somewhat modified form of construction of the casing and of the non-return valve elements, it being understood that the parts not separately mentioned are the same as in the form of construction shown in Figs. 3 to 6. The casing 4 into which the cock plug 5 is fitted, is provided at the side with two ports 50 and 51 with a common face 52 for a slide 53 and opening towards the interior of the container. This slide comprises an aperture 54, two forks 55 and 56, and a recess 57 bordered by a U-shaped rib, which recess is engaged by the head 58 of a two-armed shutting off lever 62 which

is pivotally mounted at 59 on a lug 60 pertaining to the casing 4, and which is weight-loaded at 61. A spring (leaf spring) 63 strives to keep the slide pressed against the face of the ports. This spring 63 at the same time serves to guide the 5 slide, since the spring engages in the forks 55 and 56. Furthermore, the spring is so bent at 63^a that it rides up on to the edge 55^a in the fork 55 on the descending of the slide, with the result that the slide is more firmly pressed against the 10 face 52 in the position of closure. On the tilting of the device shown in Fig. 7 through 90° and in a clockwise direction, which corresponds to the standing up of the container for the purpose of refilling it with liquid, the weight swings in opposite direction, and thereby displaces the slide in a downward direction up to the stop 65, so that the two ports 50 and 51 are closed off. Filling can therefore only be carried out by such persons as are in possession of the key to the cylinder lock which, when unlocked, permits of the removal of the cock plug bodily from the casing.

I claim:

1. A tapping and refill-controlling device for a container of marketable liquid, comprising in combination a tapping cock consisting of a casing and a fitted plug, ports in said casing and said plug adapted to be brought freely into and out of registry by rotation of said plug to permit unrestricted draining and closure of the container by 30 said plug; an outwardly opening check valve interposed in the outflow path of said cock to prevent filling of the container through said plug, disengageable retaining means associated with said plug and casing for normally retaining said 35 plug against withdrawal from said casing, and a lock built into said cock in operative association with said retaining means for permitting the withdrawal of said plug from said casing and the use of the latter as a refill aperture only by the 40 disengagement of said retaining means in dependence on the operation of said lock.

2. A tapping and refill-controlling device for a container of marketable liquid, comprising in combination a tapping cock consisting of a casing and a fitted plug, ports in said casing and plug adapted to be brought freely into and out of registry by the rotation of said plug to permit unrestricted draining and closure of the container, and an outwardly opening check valve 50 interposed in the outflow path of said cock to prevent filling of said container through said plug, disengageable retaining means associated with said plug and casing for normally retaining said plug against withdrawal from the casing, 55 said retaining means comprising an annular groove in the inner end of said plug and a latch arm having an arcuate edge adapted to normally engage in said groove to retain the plug in said casing, and a lock built into said cock and having 60 its operating elements connected with said latch arm to actuate the latter to hold the plug in its casing or to release it in accordance with the operation of the lock, to permit the withdrawal of said plug and the use of said casing as a refill 65 aperture only by the release operation of said lock.

3. A tapping and refill-controlling device for a container of marketable liquid comprising in combination a tapping cock consisting of a casing and a fitted plug, ports in the said casing and plug adapted to be brought into and out of register by rotation of the said plug, disengageable retaining means associated with the said plug and casing for normally retaining the said plug 75

against withdrawal from the said casing, an outwardly opening valve mounted in the said plug and interposed in the outflow path of the said cock, and a lock built into the said plug in operative association with the said retaining means, for the purpose of enabling the said plug to be withdrawn from the said casing, thereby providing a refill aperture, after disengagement of the said retaining means in dependence on the operation 10 of the said lock.

4. A tapping and refill-controlling device as claimed in claim 3 in which the said retaining means comprise pivoted latch elements mounted on the inner end of the said plug with a range 15 of pivotal movement extending from a position within the peripheral contour of the said end of the plug to a position at least partly overlapping the surface of the said end, and spreading means coupled with the said latch elements and operatively associated with the said lock for pivotal movement of the said latch elements in dependence on operation of the said lock.

5. A tapping and refill-controlling device for a container of marketable liquid comprising in combination a tapping cock consisting of a casing 20 and a fitted plug, ports in the said casing and

plug adapted to be brought into and out of register by rotation of the said plug, disengageable retaining means associated with the said plug and casing for normally retaining the said plug against withdrawal from the said casing, a slide 5 valve adapted to coact with the face of the port in the said plug on the side towards the interior of the said container, means for resiliently pressing the said slide valve against the said face, gravity operated means for moving the said slide 10 valve into the position of closure on the tilting of the said container from the tapping position into a refilling position, and a lock built into the said cock in operative association with the said retaining means, for the purpose of enabling the said 15 plug to be withdrawn from the said casing, thereby providing a refill aperture, after disengagement of the said retaining means in dependence on operation of the said lock.

6. A tapping and refill-controlling device as 20 claimed in claim 5 in which the said gravity operated means consist of a two-armed lever pivoted on the said casing and having one arm in operative engagement with a recess in the said slide valve and the other arm weight loaded. 25

CHRISTOPH KARAGEORGIEFF.
